UNITED STATES PATENT OFFICE.

EMELIA STERLING, OF WORTHINGTON, MINNESOTA.

CLOTHES GUARD.

Application filed January 14, 1921. Serial No. 437,264.

To all whom it may concern:

Be it known that I, Mrs. EMELIA STERLING, a citizen of the United States, residing at Worthington, in the county of Nobles and 5 State of Minnesota, have invented new and useful Improvements in Clothes Guards, of which the following is a specification.

This invention relates to a clothes guard, for attachment to ironing boards on the 10 foldable type to prevent clothes being ironed from coming in contact with the floor upon which the ironing board is standing.

An object of the invention is to provide a clothes guard comprising a telescopic 15 frame which is detachably connected to a pair of legs of a folding ironing board and which frame has a fabric slip mounted thereon to receive the articles of clothing as they are being ironed and prevent their 20 contact with the floor.

Another object of the invention is to provide a clothes guard attachment for ironing boards which is simple in construction and may be quickly and easily attached to 25 the ironing board or detached therefrom when it is desired to fold the board for storage.

Other objects of the invention will appear in the following detailed description and in 30 the accompanying drawings wherein:

Fig. 1 is a perspective view of the ironing board showing the invention applied.

Fig. 2 is a plan view of the clothes guard.

Fig. 3 is a longitudinal section through 35 the improved clothes guard.

Fig. 4 is a detailed cross section through the clothes guard showing one of the attaching members.

Referring more particularly to the drawings the improved clothes guard comprises 40 a supporting frame 1 including side members of rails 2 and 3 each of which includes a pair of telescopic connected sections 4 and 5 which permit adjustment of the length 45 of the clothes guard. The ends of the side rails 2 and 3 are curved inwardly towards each other as shown at 6 and the ends of the sections 5 of the side rails 2 and 3 receive therein the spring plugs 7 of the attaching clamps 8. The plugs 7 are substantially cylindrical in shape being split 50 as shown at 9 and having their ends remote

from the attaching plate 8 spaced as shown at 10 to impart resilient spreading action to the plugs, to cause them to frictionally grip the inner surface of the curved ends 6 of the sections 5 of the side rails 2 and 3. The attaching plates 8 are attached to the legs C of an ordinary folding ironing board in any suitable manner, and by slipping the curved ends 6 onto the plugs 7 the clothes guard attachment may be quickly and easily attached to the ironing board structure. Supporting hooks 11 are carried by the legs C of the ironing board structure 65 and engage the side rails 2 and 3 for supporting them against pivotal movement on the plugs 7 as pivots. A slip or covering 12 of any suitable material is mounted over the frame 1 to receive thereon the clothes 70 being ironed and prevent contact of the clothes with the floor.

It is, of course, to be understood that the invention may be constructed in various other manners and the parts associated in 75 different relations and, therefore, I do not desire to be limited in any manner except as set forth in the claims hereunto appended.

Having thus described my invention what I claim is:

1. In combination with an ironing board including legs, of a clothes guard comprising a frame including side rails composed of telescoping sections, certain ends of said sections being inturned and hollow and outwardly extending plugs carried by certain of said legs and adapted to have binding action with the hollow ends of said sections, and hooks carried by certain of said legs and engaging the frame when in operative position.

2. In combination with an ironing board including legs of a clothes guard comprising a frame having inturned ends that are hollow, split plugs carried by certain of 95 said legs and adapted to have detachable binding action with the inturned ends of the frame, hooks carried by certain of said legs and engaging the frame when in operative position, and a slip mounted on said 100 frame.

In testimony whereof I affix my signature.

MRS. EMELIA STERLING.
